(57) **CLAIM**

The ornamental design for a heater for semiconductor manufacturing, as shown and described.

DESCRIPTION

FIG. 1 is an enlarged front elevation view of a heater for semiconductor manufacturing showing our new design;

FIG. 2 is an enlarged left side elevation view, the right side being a mirror image thereof;

FIG. 3 is a top plan view thereof;

FIG. 4 is a bottom plan view thereof;

FIG. 5 is an enlarged top plan view of the area 5—5 shown in FIG. 3; and,

FIG. 6 is an enlarged bottom plan view of the area 6—6 shown in FIG. 4.

The broken lines shown in the figures are for illustrative purposes only and form no part of the claimed design.
